UNITED STATES PATENT OFFICE.

GEORGE R. DOBBINS, OF LOS ANGELES, CALIFORNIA, ASSIGNOR OF ONE-TENTH TO WILLIAM F. SCHANBACHER, OF LOS ANGELES, CALIFORNIA, ONE-TWENTIETH TO LEONARD KILL AND ONE-TWENTIETH TO JOSEPH H. GOSLING, BOTH OF SANTA MONICA, CALIFORNIA, AND TWELVE AND ONE-HALF PER CENT. TO ROY W. BIDDLECOM, OF FRESNO, CALIFORNIA.

ADJUSTABLE FRAME FOR AUTOMOBILE-TOPS.

1,333,798.

Specification of Letters Patent. Patented Mar. 16, 1920.

Application filed July 3, 1918. Serial No. 243,092.

To all whom it may concern:

Be it known that I, GEORGE R. DOBBINS, a citizen of the United States, residing at Los Angeles, in the county of Los Angeles and State of California, have invented a new and useful Adjustable Frame for Automobile-Tops, of which the following is a specification.

This invention pertains to folding frames for the tops of vehicles and more especially to that type of frame that can be readily opened and closed by one person.

An object of the invention is to produce a top frame of maximum simplicity of construction and operation combined with strength and rigidity of construction.

Another object is to make provision for readily changing existing tops having two vertical bows so as to eliminate one of the vertical bows, thus to produce neater appearing tops.

Another object is to produce a top frame which can be readily adjusted to fit various sizes of automobiles.

Other objects and advantages will appear in the subjoined detailed description.

The accompanying drawings illustrate the invention.

Figure 1 is a longitudinal mid section of the invention.

Fig. 2 is an enlarged detail of one of the frame joints shown in Fig. 1.

Fig. 3 is a reduced elevation transversely of the frame partly in section on line indicated by x^3-x^3 , Fig. 1.

Fig. 4 is a perspective view of one of the arm sections.

Fig. 5 is a perspective view of the connection member.

Fig. 6 is a perspective view of the forward portion of the other section of the arm.

A fragment of the vehicle body is shown at 1 and pivoted thereto at 2 are bows 3 and 4, the bow 3 being in vertical position when the top is up and the bow 4 extending aslant rearward and upward. From the nature of the view, Fig. 1, only one of the pivots 2 is shown and only one-half of each bow is shown. The bows 3 and 4 are of the usual

inverted U-shape construction and are similar to those employed on many automobiles. Only one side of the frame is shown in Fig. 1 because of the nature of the view.

The bow 3 is provided with ears 5 which embrace the rear end of an arm 6 that may be composed of one or more devices and, in this instance, is formed of two sections or members, there being a removable pin in the form of a bolt 7 inserted through the ears and arm to detachably connect the arm 6 and bow 3 to one another. The bolt 7 is provided with a wing-nut 7'. The rear section of the arm 6 is provided with a series of holes 8 arranged at intervals longitudinally thereof near its forward end so that it may be adjustably fastened by a bolt 9 to the forward section 10 of the arm 6, the bolt passing through a hole 12 in the forward section 10 and through a notch 13 in an attaching member 11. On the bolt 9 is a wing-nut 14 and it is clear that when the wing-nut 14 is loosened the arm 6 may be readily detached from the attaching member 11. The attaching member 11 is riveted or otherwise fastened at 15 to a U-shaped bow 16. The bow 16, if desired, may be formed by merely cutting off the end portions, indicated in dotted lines a , of the forward vertical bow ordinarily furnished with some types of automobile tops.

The member 11 is provided at its forward end with a laterally projecting abutment formed by an ear 17 which is adapted to engage the upper edge of an offset portion 18 of the arm 6. The forward end of the offset portion 18 is provided with a laterally projecting abutment formed by an ear 19, preferably curved to fit the top and sides of a U-shaped horizontal bow 20. The bow 20 may correspond with the usual horizontal bow found in some types of automobile tops, said bow as originally furnished on said automobiles being indicated in dotted lines b , Fig. 1. The bow 20 is provided at its rear end with a laterally projecting stud 21 passing through a hole or eye 22 in the arm 6. The hole 22 passes through an offset portion 25 of the member 10 and the forward end of

said offset portion is provided with a laterally projecting abutment formed by an ear 26 which may be curved so as to fit the top and sides of the bow 20, as clearly shown in Fig. 4. It is understood that each vehicle will be equipped with two sets of the frame elements described above with the exception of the bows 3, 4, 16 and 20, one set for each side of the frame, but only one set is described and shown in the drawings as the two sets are exact complements of one another.

From the foregoing it is readily seen that the members 10, 11, bolt 9 and wing nut 14 constitute connection means between the bow 16 and bow 20, that such connection means are provided with the eye 25 to receive the stud 21, and that the screws 15 serve to fasten the connection means to the bow 16. These connection means may be otherwise constructed than shown and described above, and it is clear that the eye 25, stud 21 and abutment or ear 26 are essential to functioning of the device.

The frame constituted as above described is adapted to support a cover 27 which extends over the intermediate portions of the bows 3, 4, 16 and 20. The cover 27 may be made of any suitable material and is fastened by any of the usual means to the bows.

In practice, when the top is in the unfolded position the parts are as shown in Fig. 1. To collapse the top the operator will detach the top from the front support 28 in the usual manner and he will unscrew the wing-nuts 7 at both sides of the frame and remove the bolts 7. He will then unscrew the wing-nuts 14 and move the members 11 laterally sufficiently far to move the ears 17 out of engagement with the upper edges of the arms 6. When this is done the rear ends of the arms 6 swing downward about the axes of the studs 21 so as to raise the ears 19, 26 from engagement with the bow 20. When the operator will move the forward sections 10 upward sufficiently far to withdraw them from engagement with the studs 21, thus detaching the arms 6 and members 10, 11 from the remainder of the frame parts so that the arm 6 and said members can be stored away until it is desired to open or unfold the top. Then the operator will move the bow 20 rearward and engage the studs 21 with eyes 29 on the end portions of the bow 3. Then he will swing the bow 20 rearward against or close to the bow 3 and he will continue to move the bow 20 rearward and with it the bow 3 until said bows are close to the bow 4. He will then swing all of the bows together rearward and downward to bring the top into the folded position, as is readily understood.

It is to be noted that by cutting off the forward vertical bow of existing automobile top frames and fastening thereto the members 11 and that by fastening the ears 5 to

the bow 3 the existing top frames of many types of automobiles may readily be converted into my improved top frame which is devoid of any support between the bow 3 and front supports 28.

While I have illustrated in my drawings and explained a preferred form of the embodiment of my invention, this form is of course a mere specific construction. There are numerous specific constructions of my invention which might be substituted for the preferred form illustrated and I do not intend to limit the scope of my invention to the preferred form referred to, and in fact, generically, my invention is of the breadth and scope set forth in the annexed claims.

I claim:

1. An adjustable frame for automobile tops comprising a bow adapted to be pivoted to the top of an automobile, a second bow, arms detachably connected with the first named bow and provided with laterally projecting ears respectively, attaching members connected to each of the arms and provided with laterally projecting ears, the attaching members being fastened to the second bow and the ear of each of said attaching members being adapted to engage the top of the associated arm, and a third bow having a stud passing through each of the arms, the ears of the arms being adapted to engage the top of the third bow.

2. An adjustable frame for automobile tops comprising a bow adapted to be pivoted to the top of an automobile, a second bow, arms detachably connected with the first named bow and provided with laterally projecting ears respectively, attaching members provided with ears, means adjustably connecting the attaching members to the arms respectively, the attaching members being fastened to the second bow and an ear of each of said attaching members being adapted to engage the top of the associated arm, and a third bow having a stud passing through each of the arms, the ears of the arms being adapted to engage the top of the third bow.

3. A frame for automobile tops, comprising a rear vertical bow, a forward vertical bow of less height than the rear vertical bow, a horizontal bow, horizontal arms, means connecting the rear ends of said arms to the rear vertical bow, means connecting the said arms intermediate of their ends to the said forward vertical bows, and laterally projecting ears formed on said arms adapted to engage the upper surface of said horizontal bows.

4. In a frame for automobile tops, the combination with a rear vertical bow and a horizontal bow, of horizontal arms secured to said rear vertical bow and provided with laterally projecting ears engaging the upper face of said horizontal bow.

5. In combination, an arm adapted to be connected to a rear vertical bow of an automobile top and having means at its forward end to engage the upper face of a horizontal bow of said top, said arm having an orifice adapted to receive a stud on the horizontal bow, and an element adapted to be secured to a forward vertical bow of the top and

coöperating with the arm to support the horizontal bow.

Signed at Los Angeles California, this 27th day of June, 1918.

GEORGE R. DOBBINS.
